ABSTRACT OF THE DISCLOSURE

An ignition tube with one end sealed into a flashbulb and its other end projecting externally of the bulb is filled with flash material (such as shredded zirconium foil). The end of the ignition tube projecting externally of the bulb is pre-formed in a specified region and shaped to have a rectangular or similar cross-section so that it has one long and one short cross sectional dimension, to avoid the necessity of substantial deformation upon being struck an ignition blow; the percussive type ignition material is located, at least partly, in the deformed region, preferably encapsulated as a separate structural element.

CROSS REFERENCE TO RELATED
APPLICATION

U.S. application Ser. No. 838,758, filed July 3, 1969, now patent No. 3,624,824, and U.S. Ser. No. 59,581, filed July 30, 1970.

The present invention relates to flashbulbs which are ignited by a percussive ignition mixture, in which combustible flash material is located in a bulb, together with a combustion supporting substance such as oxygen. A small metallic tube is sealed into the bulb, in communication with the interior of the bulb, and contains percussion-sensitive material to ignite the actual flash material within the bulb.

Percussively ignited bulbs are flashed by applying an impact, such a hammer blow to the side of the metal tube, for convenience hereinafter referred to as the ignition tube. Preferably, the blow is provided by a pair of counter-acting hammers, swinging in a direction perpendicular to the axis of the ignition tube, to avoid unbalance and possible blurring of a photographic picture to be taken. The blow against the ignition tube causes deformation thereof. The blow damages the tube and requires a certain amount of force.

It is an object of the present invention to improve lamps of the percussive-ignition type by reducing the required impact to ignite the tube and to reduce the danger of destruction of the ignition tube.

SUBJECT MATTER OF THE PRESENT
INVENTION

Briefly, the ignition tube is pre-formed in a specified region beyond its seal to the bulb, and shaped such that the cross-section has a smaller and a larger diameter, for example, to be in rectangular, or similar form. Pre-deformation of the tube, so that one diameter is less than the other decreases the amount of force required to ignite the percussive material, and avoids the necessity of a substantial deformation of the tube by the percusion hammer during ignition, itself; while, simultaneously, providing for a suitable location and attachment of the percussive ignition material within the interior of the tube.

The impact energy required to ignite the percussive

2

material is less than the impact force required for a cylindrical tube, since the distance of the wall surfaces of the tube, in the pre-deformed region is already substantially decreased. Decrease of the required impact energy decreases the probability of blurred images due to camera movement. Additionally, the ignition tube, which is frequently closed by cold press welding is less likely to tear during ignition of the percussive material, which results usually in incomplete combustion of the combustible material within the bulb and blackening thereof.

The invention will be described by way of example with reference to the accompanying drawings, wherein:

FIG. 1 is a schematic longitudinal sectional view through a flashbulb;

FIG. 1a is a detail view of the ignition tube;

FIG. 2 is a top, cross-sectional view of a percussion cap, i.e. a fire loaf;

FIG. 2a is a longitudinal side view of the percussion cap of FIG. 2;

FIG. 3 is a fragmentary cross-sectional view of the ignition tube in longitudinal section;

FIG. 4 is a different embodiment of the invention, similar to FIG. 3;

FIG. 5 is a longitudinal cross-sectional view of the ignition tube having a percussion cap, i.e. a fire loaf and a carrier;

FIG. 6 is a longitudinal cross-sectional view of the ignition tube with an ignition cap and a carrier, which serves as an anvil; and

FIG. 7 is a longitudinal sectional view of an ignition tube with a carrier partly having percussive material applied thereto.

The flashbulb (FIG. 1) has a light transparent tubular bulb 1 filled with a combustible material 2, for example, shredded zirconium foil, and oxygen of approximately 7 atm. The tube may be sealed by any convenient means, for example, by a metal exhaust tube 3, for example, of copper, sealed off after evacuation and filling of the lamp. The other end of the bulb 1 has a small metal tube 4, preferably also of copper, sealed into the bulb 1 which is cylindrical in the region extending within the bulb. The region A just beyond the bulb is likewise cylindrical; the next adjacent region, B, however, is pre-deformed by being squeezed or pressed together—see FIG. 1a. The metal tube 4, which forms the ignition tube is so pre-deformed that two wall sections 4a result, located opposite each other, defining an acute angle and substantially flat, pressed together along zone a of section B with such pressure that, by cold-press welding, a vacuum tight, pressure resistant end closure of the tube 4 is formed. Additionally, the press may be soldered. Zone b of the section B includes ignition material 6 which extends over and up to zone c of the section B. The ignition material may, for example, be a mixture of powdered zirconium, potassium chlorate, red phosphorus, aluminum oxide and binder.

The ignition material itself, for example, has the form of a center bit m of an ignition cap 7, known as a fire loaf, such as used, for example, in toy guns, cap pistols and the like. Such ignition caps, i.e. fire loafs are formed of two adhered paper layers, usually colored red, between which a mixture of red phosphorus and potassium chloride, mixed with gum arabic is located. The center bit m of such fire loafs contains approximately half of the amount of percussive ignition material as that used in toy pistol caps, that is approximately 0.5 to 3 mg. Such a cap may be held by being squeezed between the two wall sections 4a in the zone b; approximately 1 to 2 mm. extending free into the zone c of the section B. Thus, an ignition spark caused by impact against the tube 4 can freely expand into the interior of the bulb, to start ignition of the combustible material therein; alternatively, and as shown

in FIG. 1, the pressure wave caused by ignition of cap 7 can cause an additional primer bead 5 to ignite which, in turn, causes ignition of the combustible material within the interior of the bulb. The primer bead 5 is frequently not necessary since combustion of the flash-generating material within the bulb 1 can frequently be started directly by the cap 7.

The invention can be used with percussive ignition material inserted into the tube in various ways. FIG. 3 illustrates section B of the ignition tube 4 which particularly in the zone b is filled with powdered percussive ignition material, closed off by means of a stopper 8, for example, made of metal or plastics. Upon deformation of the ignition tube, for example, by an impact in the direction of the arrows the stopper is ejected by the pressure of the ignition into the interior of the lamp to enable the ignition spark to spread.

Embodiment of FIG. 4: The ignition material is located within an encapsulating housing to form a cap 9 which tears upon ignition of the percussive material. The cap 9 can be made of metal, such as copper, thermoplastic material, paper or other suitable substances. The cap 9 is located between the flat wall sections 4a, by being pinched therebetween, and located in the zone b, and extends clear into the zone c. Ignition of the lamp is initiated by a short impact in the direction of the arrows (FIGS. 1, 3, 4) by means of a hammer mechanism, preferably a dual hammer mechanism acting on both flat wall sections of tube 4 within the section b, and preferably against the center of the ignition material.

Embodiment of FIGS. 5 to 7: The center bit m of a fire loaf (FIG. 5) an ignition capsule 9 (FIG. 6) or an ignition mass 12 (FIG. 7) is located on a carrier 10 which may, for example, be a small plate of hard material such as steel. The ignition material, that is the fire loaf or capsule, or the like may be adhered to the carrier plate 10. The ignition mass 12 may be covered with a foil 13 such as paper, cardboard, thermoplastic material or the like. The carrier can be formed with a plastic ring 11 and it is frictionally held by the squeezed-together wall sections 4a. The carrier plate 10 forms a support which has the function of an anvil, thus providing for reliable ignition even with small percussive energy. According to the embodiments of FIGS. 5 to 7, the percussive energy can be applied by a single-sided blow by means of a hammer mechanism, as indicated in FIGS. 5 to 7 by the arrow. The impact is directed solely to the flat wall section 4a of the metal tube 4 which is immediately adjacent the ignition material.

During manufacture of flashbulbs of the present invention, it is preferred to insert the ignition material in the form of small caps, (fire loafs), capsules or carriers with ignition material in any form, for example, either from below through the metallic tube 4 and then slowly squeezing the tube together. Alternatively, the ignition material, for example, in powdered state may be filled into an already closed metal tube from a direction of the interior of the lamp.

The present invention has been illustrated and described particularly in connection with small photographic-type flashbulbs; various changes and modifications may be made within the scope of the inventive concept to meet design requirements.

We claim:

1. Flashbulb having a transparent bulb containing combustible material and a combustion supporting substance
  - a tubular extension of deformable material projecting from said bulb, forming an ignition tube, extending into said bulb and being sealed thereto, the ignition tube being unobstructedly open at its inner end which extends into the bulb and being closed at the other end;
  - the tube being flattened and pre-deformed in the projecting region to have a shape such that its cross-section has a dimension which is substantially less than the diameter of the tube at its seal to the bulb to avoid substantial deformation upon percussion against the tube;
  - and percussive type ignition material contained within the tube and located at least partly within the flattened pre-deformed region.
2. Flashbulb according to claim 1, wherein said ignition tube is of metal.
3. Flashbulb according to claim 1, wherein the ignition tube has a first portion (A) adjacent the bulb which is cylindrical in cross section;
  - and a second next adjacent portion (B) which is squeezed out-of-round to be flattened and to form a pair of opposite wall sections which, between themselves, define a small acute angle;
  - and said percussive type material is located in said second section.
4. Flashbulb according to claim 3, wherein;
  - a stopper is provided closing off the tube containing the percussive material towards the bulb.
5. Flashbulb according to claim 3, wherein the percussive material is enclosed in a cap and said cap is pinched between the wall sections.
6. Flashbulb according to claim 3, wherein the percussive material has the form of a center bit (m) of an ignition cap, forming a fire loaf.
7. Flashbulb according to claim 3, wherein the percussive material is encapsulated in a plastic cap.
8. Flashbulb according to claim 3, wherein the percussive material is encapsulated in a metal cap.
9. Flashbulb according to claim 3 including a support carrier, said percussive material being applied to said support carrier.
10. Flashbulb according to claim 9, including a ring of thermoplastic material securing said support carrier within said pre-deformed region.
11. Flashbulb according to claim 9, wherein the support carrier is pinched between the acute angle formed by said flattened opposed wall sections.
